UNITED STATES PATENT OFFICE.

JOHN A. HEALY, OF LANGDON, MINNESOTA.

INSERT.

Application filed June 3, 1927. Serial No. 197,344.

This invention relates to means for hanging pipes, machinery or other apparatus from ceilings or walls and particularly to an insert, which is adapted to be embedded in concrete, plaster or the like to anchor a supporting member therein.

It is my object to provide an insert, adapted to receive and support hangers of different kinds and sizes, whereby the selection of the 10 hanger best suited to conditions prevailing in a particular installation is permitted.

The invention will be best understood by reference to the accompanying drawings in which Figure 1 is a central, longitudinal section through the preferred form of my invention, embedded in concrete and showing a bolt in position for insertion; Fig. 2 is a transverse section through the device showing a different form of hanger therein; Fig. 3 is a bottom, 20 plan view of the preferred form of the invention; Fig. 4 is a transverse section through an alternate form of the invention; Fig. 5 is a plan view of the preferred form of nut for the hanger shown in Fig. 2 and Fig. 6 is a 25 section taken on the line 6—6 of Fig. 5.

As shown in Figs. 1 to 3, inclusive, my device consists of a hollow casting 7, which is adapted to be embedded in a ceiling or wall 8 of concrete, plaster or the like. The top and 30 sides of the casting 7 are closed and the bottom has an opening 9 into which a bolt 10 or pipe hanger 11 may be extended. Undercut, outer, side walls on the casting 7 are arranged to positively interlock with the surrounding 35 concrete. Within the casting 7 is a lower chamber 12 and an upper chamber 13. In the bottom of the chamber 13 and communicating with the chamber 12 is an opening 14 of key-hole shape, adapted to receive the head 40 15 of the bolt 10. Along the lateral edges of this opening 15 is a pair of flanges 16, arranged to support the head 15. The opening 9 in the bottom of the chamber 12 registers with the opening 14 and is also of key-hole shape 45 to receive a nut 17 upon the threaded upper end of the hanger 11. This nut 17 is preferably formed, as indicated in Figs. 5 and 6, in dish-shape with a tapered bore 18 arranged to receive the threaded upper end of the hanger 50 11.

As shown in Fig. 2, flanges 9^a supporting the nut 17, have concave, upper surfaces, which conform to the convex, bottom surface of the nut 17 and afford a pivot bearing for said hanger. Projecting from each side of 55 the casting 7, near its base, are pairs of ears 19, adapted to facilitate securing the insert upon a concrete form, as hereinafter described.

In the alternate form of my device shown 60 in Fig. 4, I provide a hollow casting 20 in which are formed chambers 21 and 22 for the nut 17 and head 15 respectively. These chambers are separated by a wall 23 and have openings 24 and 25 respectively, similar to the 65 openings 9 and 14 of the preferred construction, but upon opposite outer sides of the casting. It will be noted that the opening 24 is in one flat side 26 of the casting 20 and the opening 25 is in a parallel flat side 27. Pairs 70 of ears 28 and 29 are formed respectively in continuation of the sides 26 and 27 for securing the casting 20 upon the concrete form, said ears being similar to the ears 19 of the preferred construction. 75

In the construction of a building, before the concrete 8 is poured and after the forms therefor have been constructed, an insert or a plurality of them are secured upon the forms with the openings 9 closed by the forms. 80 Small nails may be driven between the pairs of ears 19 to hold the casting 7 in place. Now when the concrete is poured, it embeds the casting 7, as indicated in Fig. 1, and extends beneath the undercut sizes thereof to securely 85 hold it in place. When the concrete has set and the forms therefor are removed, the insert 7 is retained in the concrete and presents the openings 9 and 14 in the exposed surface of the ceiling or wall. When it is desired to 90 secure machinery, pipes or other fixtures to the insert by means of a standard bolt, such as the bolt 10 shown in Fig. 1, such bolt is inserted, as indicated in Fig. 1, in oblique position, so as to pass the head 15 through the enlarged end of the opening 14. When the head 95 has been inserted above the flanges 16, the bolt may be moved to the vertical position, indicated in dotted lines, in which position it cannot be removed from engagement with 100

the flanges 16. These supporting flanges 16 are of sufficient length to permit limited adjustment or movement of the bolt 10 within the insert. Now by turning a nut upon the 5 threaded, lower end of the bolt 10, the fixtures may be secured to the ceiling or wall. According to present practice, metal bands are frequently used to attach machinery and piping to walls or ceilings and the bolt 10 may 10 be inserted through perforations in such bands to secure them and the apparatus to the insert.

Where use of the tubular hanger 11 is considered advantageous after the insert has 15 been mounted in the wall, an object, such as a pipe 30 (Fig. 2) may be suspended therefrom, instead of from the bolt 10. To support this type of hanger, the nut 17 is threaded upon the upper end of the member 11 and 20 by reason of the tapered thread, may be turned down snugly so as to prevent accidental withdrawal by subsequent turning of the nut in the hanger. Now, by tilting the hanger 11 to one side, the nut 17 may be inserted through the enlarged end of the opening 9 and the hanger moved to vertical position, as shown in Fig. 2. A hanger ring 31 having a tapped boss 32 to receive the lower 25 end of the member 11 may be employed to support the pipe 30, or other object to be supported. The pipe 30, with the ring 31 thereon, is then elevated and the lower end of the hanger 11 is finally turned the desired distance into the threaded bore of the 30 boss 32 while rotating the nut 17 in the insert 7. The elongated opening 9 permits adjustment of the hanger 11 longitudinally of the flanges 9^a within the insert 7, while the thread on the lower end of said hanger permits vertical 35 adjustment.

With the alternate form of device shown 40 in Fig. 4, it is necessary to decide, before securing the casting 20 in place upon the form, what size or kind of hanger is to be used in the particular location, namely, whether of 45 the type of the bolt 10 or larger hanger 11. Thus, where the hanger 11 is to be used, the surface 26 of the casting 20 is placed in contact with the concrete form and the ears 28 are secured to the form. Otherwise, if bolts like 50 the bolt 10 are required in the particular location, the surfaces 27 of the castings 20 are placed in contact with the concrete form and the ears 29 are secured to the form. Now 55 when the concrete is poured, it is excluded from the lower chamber 21 or 22 and allowed to enter the upper one of said chambers. When the concrete form is removed, either 60 the opening 24 or the opening 25 is accessible for insertion of the bolts 10 or hangers 11, as above described.

As will now be understood, my improved 65 insert obviates the necessity for inserts of different sizes without substantially increasing the cost of the device. With the pre-

ferred construction, shown in Figs. 1, 2 and 70 3, it is unnecessary to decide in advance of the installation of the insert what type of hanger is to be employed or what type of fixture or piping is to be anchored by means of the insert. While I have described somewhat in detail the bolts 10 and hangers 11, it is to be understood that other types of hangers 75 may be secured in the insert and I do not wish to limit my invention to any particular hanger.

Having described my invention what I claim as new and desire to protect by Letters Patent is:

1. An insert comprising a hollow body, 80 adapted to be embedded in concrete or the like, a plurality of chambers formed in said body, said chambers having openings adapted to receive heads of different sizes on hangers and means adjacent to the several openings for supporting heads of different sizes therein.

2. In an insert, a hollow body, adapted to be embedded in concrete or the like, a plurality of chambers formed in said body, one 90 above the other, said chambers having openings adapted to receive heads of different sizes on hangers and flanges along the edges of the several openings, adapted to support heads of different sizes therein.

3. An insert comprising a hollow body, 95 adapted to be embedded in concrete or the like, upper and lower chambers formed in said body, said chambers having openings registering one with the other adapted to receive heads of different sizes on hangers and the upper chamber being accessible through the opening in the lower chamber and means adjacent to the several openings for supporting heads of widely different sizes therein. 100

4. In an insert adapted to support hangers of different sizes, a hollow body adapted to be embedded in concrete or the like, a plurality of chambers formed in said body to receive heads of different sizes on hangers, each 110 of said chambers having an opening adapted to receive a hanger and means for supporting a different hanger in each of said chambers, the several openings being elongated to permit limited movement of the hangers therein. 115

5. In an insert adapted to support hangers of different sizes, said hangers having anchoring means on their ends, a hollow body adapted to be embedded in concrete or the like, a plurality of chambers formed in said body to receive anchoring means of different sizes on hangers, said chambers having openings adapted to selectively receive said anchoring means of different sizes and means for supporting the anchoring means of a 125 hanger in each of said chambers.

6. In an insert adapted to support hangers of different sizes, said hangers having anchoring means thereon, a hollow body adapted to be embedded in concrete or the like, a 130

plurality of chambers formed in said body one above another to receive anchoring means of different sizes, said chambers having registering openings adapted to selectively receive said hangers of different sizes and means for supporting the anchoring means of a hanger in each of said chambers, the

several openings being of key-hole shape to permit insertion of the hangers with the anchoring means in place thereon.

10

In testimony whereof, I have hereunto signed my name to this specification.

JOHN A. HEALY.
